(57) **CLAIM**

The ornamental design for a cellular telephone case incorporating rotating camera lens, as shown and described.

DESCRIPTION

FIG. 1 is a rear perspective view of the cellular telephone case incorporating rotating camera lens;

FIG. 2 is a rear perspective view of the cellular telephone case incorporating rotating camera lens in use mounted to a tripod;
FIG. 3 is a front perspective view of the cellular telephone case incorporating rotating camera lens;

FIG. 4 is a front perspective view of the cellular telephone case incorporating rotating camera lens of FIG. 3 wherein the rotating lens has been rotated approximately 100°;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a top plan view thereof; and,

FIG. 10 is a bottom plan view thereof.

The broken lines immediately adjacent the shaded surfaces represent boundaries of the claimed design. All other broken lines depict unclaimed environment. The broken lines form no part of the claimed design.

1 Claim, 5 Drawing Sheets
